CLAIM

The ornamental design for an island vending machine,
as shown.

DESCRIPTION

FIG. 1 is a right front perspective view of an island vending machine showing our new design;

FIG. 2 is a right rear perspective view thereof;

FIG. 3 is a left side elevational view thereof;

FIG. 4 is a top plan view thereof.

The broken-line showings of FIGS. 1 and 2 are environmental
only and form no part of the claimed design.

FIG. 1

FIG. 2

FIG. 3

FIG. 4
